PROCESS FOR THE MANUFACTURE OF
UNSATURATED ALDEHYDES

Milton Gallagher, Louisville, Ky., and Rudolph Leonard Hasche, Kingsport, Tenn., assignors to Eastman Kodak Company, Rochester, N. Y., a corporation of New Jersey

Application September 28, 1938, Serial No. 232,160

16 Claims. (Cl. 260—601)

This invention relates to the manufacture of unsaturated aliphatic aldehydes and more particularly to a process for the manufacture of acrolein. This invention is also concerned with the manufacture of substituted unsaturated aldehydes such as, for example, α -ethacrolein and the hydrogenation products of both the aforementioned simple and substituted unsaturated aldehydes as well as other derivatives thereof.

The unsaturated aliphatic aldehydes are characterized by including a double bond in their carbon atom chain. The unsaturated aldehyde, acrolein, also referred to as acrylic aldehyde, with which this invention is particularly concerned, has the formula: $\text{CH}_2=\text{CH}.\text{CHO}$.

This application is a continuation in part of our allowed application Serial No. 88,821, filed July 3, 1936.

Unsaturated aliphatic aldehydes and, in particular, acrolein have a number of uses. As indicated, these organic compounds may be converted to other chemical products. For example, acrolein may be converted to propionic aldehyde in accordance with the procedure set forth in our copending application Serial No. 88,822 entitled "Improved method for the manufacture of propionic aldehyde," now Patent No. 2,150,158.

While liquid phase processes, known as "aldol condensation" have been carried out, wherein a single aldehyde combines with itself, and are quite well known, apparently few, if any, methods have been developed for the more or less direct manufacture of the unsaturated aldehydes and in particular unsaturated aldehydes containing an odd number of carbon atoms, with which the present invention is concerned. Prior to our invention the manufacture of higher aldehydes has been confined in a number of instances, as pointed out, to liquid phase operations or costly raw materials have been required. In the instance of acrolein, prior to our invention, acrolein has been manufactured by dehydrating glycerin (see for example Beilstein).

We have found a new method for the manufacture of unsaturated aliphatic aldehydes, and in particular unsaturated aldehydes containing an odd number of carbon atoms in the molecule such as acrolein, which is superior in a number of respects to processes previously employed in the manufacture of aldehydes.

Although our process may in some respects be considered essentially a condensation reaction, splitting off water with formation of an unsaturated aldehyde, it may be contrasted with

and differentiated from prior processes of condensation in a number of respects. For example, a single aldehyde, such as acetaldehyde, has been caused to combine with itself to form an hydroxy-aldehyde (aldol) which is later decomposed by heat to drive off water, resulting in crotonaldehyde.

We have found an efficient and highly desirable procedure wherein at least two different aldehydes may be caused to combine to produce an unsaturated aldehyde containing a number of carbon atoms equal to the sum of two aldehyde reactants.

It will be noted that prior art attempts to react two different aldehydes, have not resulted in the production of unsaturated aldehydes, but have either failed outright or resulted in the production of some other compound such as, for example, penta-erythritol from formaldehyde and acetaldehyde.

This invention has for an object to provide a process for the combination of two different aliphatic aldehydes to produce an aliphatic aldehyde containing a number of carbon atoms equal to the sum of the two aldehyde reactants. Another object is to provide a process for the production of unsaturated aliphatic aldehydes containing an odd number of carbon atoms in the molecule. A further object is to provide a process for reacting two different aldehydes in the vapor phase.

A further object is to provide a process for the reaction of the one carbon aldehyde, formaldehyde, with another aldehyde. Another object is to provide a process for reacting formaldehyde (formalin) or other source thereof, with one or more aldehydes such as acetaldehyde, propionaldehyde and butyraldehyde. Still another object is to provide a vapor phase catalyst process for the production of unsaturated aliphatic aldehydes. Another object is to provide a simple and efficient process for the production of unsaturated aliphatic aldehydes which operate readily on commercially available raw materials.

Still another object is to provide a catalytic process for the reaction of aliphatic aldehydes containing a different number of carbon atoms in the molecule. A still further object is to provide a process particularly adapted for the production of unsaturated aliphatic aldehydes such as acrolein, α -methacrolein, α -ethacrolein and the like. Another object is to provide a vapor phase catalytic process for the production of acrolein and substituted acroleins.

Still another object is to provide catalysts and

catalyst supports for process involving the reaction of aldehydes containing a different number of carbon atoms in the molecule. Another object is to provide catalysts and catalyst supports for the reaction of material containing formaldehyde with materials containing acetaldehyde, butyraldehyde or other aliphatic aldehydes.

Other objects will appear hereinafter.

These objects are accomplished by the following invention which includes the steps of catalytically reacting at least two aliphatic aldehydes having a different number of carbon atoms in the molecule. In accordance with our preferred procedure, we have found that highly desirable results may be obtained by catalytically reacting formaldehyde and acetaldehyde (or other aldehyde) in accordance with the procedure set forth herein.

For further details concerning our new process and apparatus and a more complete understanding of our invention, reference is made to the accompanying drawing which forms a part of the present application. In the accompanying drawing, in which like reference characters refer to like parts,

Fig. 1 is a diagrammatic side elevation showing an apparatus set-up for practicing our new process.

Fig. 2 is a semi-diagrammatic side elevation of a modified apparatus for carrying out our new process. In both figures certain parts of the apparatus have been shown on section or in exaggerated scale for clarity.

In Fig. 1, 2 represents a feed tank for one of the aldehydes. The tank is connected by conduit 3 through a rotameter 4 or other suitable device to vaporizer 6. Vaporizer 6 is connected by conduit 7 to mixing valve or chamber 8.

In a similar manner another feed tank 9 is provided for the other aldehyde. Tank 9 is connected by conduit 11 through a rotameter 12 to a vaporizer or boiler 13. Conduit 14 connects boiler 13 with mixing chamber 8. The feed tanks, feed heaters, boilers or vaporizers in the system will include jackets or other temperature controlling means as at 16, 17 or 18 for the purpose of regulating the temperature of the respective containers. In the apparatus shown in Fig. 1 this would be done by injection of heating or cooling fluids in the jackets as the situation required.

The mixing valve or mixing chamber 8 may be connected by conduit 19 through a heat exchanger 20 to a catalyst chamber 21. The catalyst chamber comprises the catalyst container 22 filled with catalysts. This catalyst may be retained by screens or other means as at 23 and 24. The chamber is enclosed in a temperature controlling jacket 26. This jacket may be heated by steam, hot oil, molten chemicals, electric heat or in some other suitable manner or cooling fluids may be introduced if necessary. Another jacket 29 may be provided around the catalyst chamber so that the incoming mixture may be passed in heat exchange relationship with the catalyst bed.

While we have described the above type catalyst chamber, other types of catalysts may be employed.

Catalyzer 21 is joined to condenser 27 by conduit 25. This condenser may be of the usual construction. A valve draw-off 28 is provided in order that the condensate may be withdrawn from the condenser for other use or to storage.

Fig. 2 discloses a catalytic unit for carrying out our process somewhat differently. The unit of Fig. 2 is quite similar to the unit described under

Fig. 1. A feed tank 31 is provided for one of the components. This tank is connected by conduit 46 to the mixing point 35.

Another feeding device 36 is provided for the other component. Conduit 47 connects this device with the mixing point 35. The conduit 48 leads from the mixing point to a vaporizer or flashing apparatus 32. Or, in place of the two tanks 31 and 36, the two different aldehydes may be premixed in the desired proportions and fed to the vaporizing or flashing device.

The apparatus 32 may include heating elements 33 upon which a mixture of aldehydes may be sprayed through 34. Vapors from unit 32 pass through conduit 37 to catalyst unit 39.

Catalyst unit 39 is heated or cooled as necessary by means of temperature controlling coil 41. The outside unit is insulated as at 42. Also, if desired, the line 37 may be heated. The catalyst unit includes a charge of catalyst 43. Valved conduit 44 is provided for withdrawing the reaction products to condenser or other treatment. The catalyst unit is equipped with a thermometer well 45 whereby the temperature in the interior of the catalyst may be measured. Also, as described with respect to Fig. 1, the incoming mixture may be caused to pass down the outside of the catalyst chamber, thereby absorbing heat before entering the catalyst chamber.

As already indicated, catalyst chambers 22 or 43 are filled with the catalyst. A number of catalysts have been found to be satisfactory. Silica or alumina gel, as such, are satisfactory catalysts. However, the action of these materials may be improved by impregnating them or mixing them with additional materials, such as sodium acetate, magnesium acetate, cadmium acetate, thorium, thorium oxide, molybdenum oxide or cobalt metal. While the above catalysts are satisfactory, our invention is not limited to these catalysts or catalyst supports. For example, a suitable catalyst for carrying out our process is magnesia supporting about 2-10% of metallic cobalt. Or magnesia formate, vanadium pentoxide or tungstic oxide, on a gel carrier may be employed. The temperature conditions under which any particular catalyst will operate in our process may vary somewhat. Temperatures between about 200-400° C. appear to be satisfactory, and within this range the range of about 290° C. to 300° C. appears preferable in many instances.

In more detail, there are a number of other catalysts which have been employed and which function satisfactorily in our process. Among these other catalysts, the following may be mentioned:

The following materials were tried in an amount equal to 2.5% of the weight of the support: WO_3 and V_2O_5 .

Five per cent of catalytic materials were used in the following cases: Formates of Zn, Mg, Cd, Hg, Ca, Ba, Cu, Ni^{++} , Mn^{++} , and Co^{++} . The following acetates were used at 5%: Zn, Mg, Cd, Hg, Ba, Ca, Cu, Ni^{++} , Fe^{++} , Mn^{++} , and Sr.

Five per cent of the following propionates were examined: Mg, Cd, Ca, Co^{++} , Ni^{++} , Ba, Cd and Zn.

The following were also used at 5%: $Ca(OH)_2$, Mg oxalate, $MgSO_4$, $Mg(NO_3)_2$, $MgCl_2$, $MgCrO_4$, $Tl(NO_3)_4$, Na_2CO_3 and $Na(OAc)$.

Ten per cent of the following was used: Acetates of Mg, Mn^{++} , Cd, Ba and Na, MoO_3 , thallium sulfate, $(NH_4)_2Cr_2O_7$, Na_3PO_4 , $NaCl$, $NaHAsO_4$, $NaBO_3$, $Na_2B_4O_7$, Na_2HPO_4 , $Na_2H_2PO_4$, $(NH_4)_2MoO_4$, KCl, $Be(NO_3)_2$, $Zr(NO_3)_4$, Cr ni-

trate, phosphotungstic acid, uranyl nitrate, phosphomolybdate acid and $\text{Th}(\text{NO}_3)_4$.

Twenty per cent of the following was tried: MgSO_4 , $\text{Mg}(\text{OAc})_2$, MgCl_2 , $\text{Mg}(\text{NO}_3)_2$, $\text{Co}(\text{NO}_3)_2$, $\text{Ni}(\text{NO}_3)_2$, and Na_2CO_3 .

Fifty per cent of $\text{Mg}(\text{OAc})_2$ was employed.

From 0.45 to 2.0% of the following were tested: $\text{Mg}(\text{OAc})_2$, Fe_2O_3 , ThO_2 , $\text{Th}(\text{NO}_3)_4$, K_2CO_3 , metal $(\text{AsO}_4)_2$, WO_3 , $\text{Al}(\text{OH})_3$, $\text{Cr}(\text{OH})_3$, BiCl_3 , AlCl_3 , HgCN_2 , K_2CrO_4 , $\text{Al}(\text{OAc})_3$, $\text{Mg}_3(\text{AsO}_4)_2$, V_2O_5 , $\text{Zr}(\text{NO}_3)_4$, K_2CO_3 and $\text{Th}(\text{NO}_3)_4$.

The following combinations of materials were tried as catalysts:

$\text{Mg}(\text{OAc})_2 + \text{V}_2\text{O}_5$, $\text{Mg}(\text{OAc})_2 + \text{WO}_3$
 $\text{Mg}(\text{OAc})_2 + \text{Th}(\text{NO}_3)_4$, $\text{Mg}(\text{OAc})_2 + \text{Zr}(\text{NO}_3)_4$
 $\text{Mg}(\text{OAc})_2 + \text{K}_2\text{CO}_3$, $\text{Mg}(\text{OAc})_2 + \text{Be}(\text{NO}_3)_2$
 $\text{Mg}(\text{OAc})_2 + \text{Ce}(\text{NO}_3)_2$, $\text{Mg}(\text{OAc})_2 + \text{heavy metal acetate}$
 $\text{Na}(\text{OAc}) + (\text{NH}_4)_2\text{MoO}_4$, Mg oxalate + $\text{Co}(\text{NO}_3)_2$
 $\text{MgCrO}_4 + \text{K}_2\text{CO}_3$, Mn salts + K_2CO_3
 $\text{MgCrO}_4 + \text{CO}(\text{NO}_3)_2$
 $\text{MgCrO}_4 + \text{Co}(\text{OAc})_2$
 $\text{MgCrO}_4 + \text{K}_2\text{CO}_3 + \text{Co}(\text{OAc})_2$
 $\text{MgCrO}_4 + \text{Ni}(\text{OAc})_2$
 $\text{MgCrO}_4 + \text{Ni}(\text{OAc})_2 + \text{K}_2\text{CO}_3$

A number of combination catalysts of MgO were prepared with at least one of the following materials: Co , $\text{Ba}(\text{OH})_2$, Fe_2O_3 , H_3PO_4 , ThO_2 , V_2O_5 , WO_3 , $\text{Ce}(\text{NO}_3)_2$, AgO , Cd , Ag , Cu , Co .

The aforementioned catalysts were prepared by the following methods:

A. To 100 g. of silica gel was added an aq. acid solution prepared by adding 15 cc. of strong acetic acid to 35 cc. of water, followed by gentle warming and the addition of 10 g. of ZnO , MgO , NiCO_3 , CdO or any other basic oxide or carbonate or hydroxide of the desired metal. Any excess liquid was removed by heating either with or without reduced pressure.

B. To 100 cc. of silica gel treated as above was added 10 g. H_2SO_4 diluted to 30 cc. with water. By this procedure the above acetates were completely converted to the corresponding sulfates precipitated directly on or within the pores of the gel.

C. To 100 cc. of silica gel was added 10 g. H_2SO_4 to which had been added 25 cc. H_2O . To this gel so treated was added the aq. acid solution of the metal salt as prepared in (A). This accomplished essentially the same results as (B) but produced a more active catalyst.

D. Similar procedures were followed in preparing chromates, phosphates, molybdates, etc.

The other catalysts described above may be prepared by the same general steps A, B, C already set forth. It is to be understood that while in the process examples sulphuric acid and other such specific agents have been described, other inorganic and organic acids or chemicals may be employed. For example, in place of the sulphuric acid, phosphoric could be employed.

While in the above examples in many instances the impregnating or mixing metal or metal salts was employed in amounts from 45% to 5 or 10%, it will be observed that amounts as high as 50% were employed. Therefore, while we prefer a base impregnated or mixed with a minor proportion of a metal or metal salt, we do not wish to be restricted to these embodiments inasmuch as the proportions may be varied. We have also found that the silica gel and alumina gel may be mixed in varying proportions.

For convenience, we designate our catalysts generically as "dehydrating catalysts." The com-

bination catalysts comprising supports such as gels, charcoal, magnesia, or the like, impregnated or mixed with the various metals and metal salts specified, we sub-generically designate as "impregnated" or "mixed dehydrating catalysts."

The operation of our new process and apparatus may be better understood by reference to the following examples which are set forth merely for the purpose of illustration. The following example is described as carried out in the apparatus of Fig. 2.

The container 31 was filled with a relatively pure liquid acetaldehyde. The acetaldehyde was permitted to flow to the mixing point 35. Container 36 was filled with formalin, and this material was permitted to flow through conduit 47. The desired amount of acetaldehyde was mixed with formalin at 35. This mixture was conducted through conduit 48 into flashing apparatus 32. The mixture of acetaldehyde and formalin flowing from 34 over heating means 33 vaporizes and was conducted through conduit 37 to catalyst unit 39.

The catalyst unit had been heated and during the reaction was maintained in a heated condition by means of an electrical heating coil 41.

During a run of about six hours, approximately 101.3 grams of acetaldehyde and approximately 84 grams of formaldehyde fed as formalin containing approximately 35% formaldehyde by weight were fed to the catalyst unit. The catalyst chamber, which was filled with one of the aforementioned catalysts, was held at about 285° C. by electrical heating. It is highly desirable that a temperature above 225° C. and preferably above 250° C., be employed. After a period of operation, which may be from 12 to 24 hours, the catalyst may be regenerated.

It is also preferred to employ excess acetaldehyde (or other aldehyde higher than formaldehyde) in carrying out our reaction. By this procedure substantially all the formaldehyde is converted. This is also advantageous because it minimizes any difficulties of separating formaldehyde from the reaction products.

The acrolein containing materials were drawn off at 44, where the acrolein could be recovered as such if desired.

However, in the example under description it was desired to convert the acrolein to propionic aldehyde. Therefore, the acrolein produced in catalyst unit 39 was conducted through 44 to a hydrogenation apparatus (not shown), wherein hydrogenation was carried out consuming approximately 14.42 grams of hydrogen. This treatment resulted in a yield of approximately 51.8 grams of propionic aldehyde. This yield of propionic aldehyde indicates that a satisfactory yield of acrolein was obtained in the preceding step, inasmuch as hydrogen reacts with acrolein in accordance with the following reactions:

The following example is described with respect to Fig. 1. Tank 2 was filled with commercial acetaldehyde. Inasmuch as acetaldehyde has a boiling point of about 21° C. it may be desirable to circulate a cooling medium in jacket 16 to prevent volatilization of the aldehyde. In place of the cooling jacket it is, of course, apparent that cooling coils may be immersed in the acetaldehyde. The acetaldehyde is fed through

rotameter 4 into vaporizer 8. Acetaldehyde vapors from 8 are conducted to mixing chamber 9.

In our process it is possible to use acetaldehyde from various sources. For example, the acetaldehyde may be obtained synthetically from acetylene. The acetylene may be produced from calcium carbide, cracking hydrocarbons or the decomposition of hydrocarbons in an electric arc. The acetaldehyde may also be obtained from ethyl alcohol.

Formaldehyde (or materials containing formaldehyde) is placed in container 8. This container may be heated or cooled or otherwise acted upon dependent upon the particular formaldehyde material.

Relatively pure formaldehyde boils at approximately -21° C. Formalin, which contains around 40% of formaldehyde, the remainder being principally methyl alcohol and water, is an easier source of formaldehyde to work with. Also formalin is readily available commercially. We have found that the methyl alcohol content of formalin or other sources of formaldehyde does not interfere with our process. Solid para-formaldehyde may be employed. It is, therefore, apparent that our invention embraces various sources of formaldehyde. We also contemplate the added steps of converting methyl alcohol into formalin and feeding the resultant reaction mixture through conduits 11 and 14.

In the example under description the formaldehyde materials were fed through rotameter 12 into the formaldehyde boiler 13. The evolved vapors containing formaldehyde were conducted through conduit 14 to the mixing point 8.

From the vapors containing formaldehyde and acetaldehyde with or without water, methyl

covered as such and employed, or, as described with respect to the preceding example, the acrolein may be converted to different chemical compounds by hydrogenation or other treatment. Excellent yields of acrolein were obtained.

The above examples are merely illustrations of conditions for carrying out our process. The re-

action conditions may be varied and the above examples are not to be construed as limiting our invention. For example, the mole ratio of acet-aldehyde to formaldehyde may be varied.

aldehyde to formaldehyde, while generally kept within the range of from 5-0.5 may be varied outside of these limits. The high ratio is desirable because the yield based on formaldehyde is

15 able because the yield based on formaldehyde is smaller than the yield based on acetaldehyde, and we have found that a more complete utilization of the formaldehyde could be obtained by using a higher formaldehyde to acetaldehyde ratio.

20 The use of excess acetaldehyde has other advantages, as indicated above.

The space velocities for the formation of acrolein may vary according to conditions and reaction equipment. We have found a range from

25 200-3000 to be suitable for carrying out our reaction. We may define "space velocity" as cubic feet of reactants fed per cubic foot catalyst per

hour,—volumes of reactant materials measured at temperatures and pressures of reaction. As 30 already indicated, the temperature range may vary from about 200° C. to 400° C., while

vary from about 200° C. to 400° C. While we prefer to carry out the reaction under atmospheric conditions, it is possible to carry out the reaction under either higher or lower pressures.

35 Further examples illustrating the operation of our process may be observed from the following runs in tabulated form:

Run No.	Tem- pera-ture range	Feed ratio CH ₃ O/AcH	Space velocity	Catalyst data	
				Support	Catalyst
36	280-300 °C.	0.449	338	MgO pellets	Cobalt.
45	270-300	0.368	301	do	Wos.
49	280-300	0.464	673	Silica gel	
13A	300	0.616	620	Al ₂ O ₃	
20A	300	0.692	650	do	5% Mg ₂ O ₃
35A	300	0.650	672	do	Wos+Mg ₂ (OAc) ₃
40A	355	0.67	1870	do	20% Co (No) ₂
78	335	0.83	1840	Silica gel	10% Mg ₂ (OAc) ₃
2-65	306	0.45	950	do	5% Ca (OAc) ₂
2-67	310	0.45	960	do	5% Ba propionate
5-21	300	0.45	945	Silica aero gel	5% Ca acetate

alcohol and the like, pass into and through catalyst 22. This catalyst, comprising either silica or alumina gel, was heated to approximately 290° C. to 300° C.

The following reaction apparently took place:

The vapors from the catalyst chamber coming off at 25 are passed through cooling device 27. At 28 acrolein containing some water, unreacted formaldehyde and acetaldehyde may be withdrawn. The unreacted components may be separated and recirculated if desired.

As indicated above, the acrolein may be re-

Our novel procedure described herein represents a particularly satisfactory method for the manufacture of unsaturated aliphatic aldehydes containing an odd number of carbon atoms. Our preferred embodiment for the manufacture of acrolein permits the utilization of materials, such as formalin and acetaldehyde.

60 While our process is particularly adapted for the preparation of unsaturated aliphatic aldehydes as described in the above examples, our invention has wider applications and embraces simi-

65 lar procedure for the formation of other such products. An example of the formation of an unsaturated aldehyde with an even number of carbon atoms is the reaction between formaldehyde and propionaldehyde to form a methacrylic-aldehyde.

70 It will be observed that by our process of reacting with formaldehyde, aldehydes of higher molecular weight than acetaldehyde, there may be obtained an alkyl group in the alpha position. Such α -substituted type of compound has value
75 in synthetic resin production and other similar

uses. For a further example, formaldehyde combines with normal butyraldehyde to form α -ethacrolein in accordance with the following equation:

Thus we have discovered a process which will form any of the substituted acroleins in which we may be interested.

This reaction of formaldehyde with other aldehydes higher than acetaldehyde goes with greater ease and with higher yields than produced in the manufacture of acrolein by the aforescribed reaction of formaldehyde with acetaldehyde. The catalyst does not become foul or lose its activity to any great degree even with extensive use in these processes for reacting formaldehyde with 3-carbon atom, 4-carbon atom or higher aldehydes.

Our process does not require the utilization of high pressures which is believed to be unusual for a process of this type. Our process is also particularly desirable from the standpoint that any by-products produced are few in number and in relatively small quantities when our process is properly employed. Any unreacted components may be reutilized by circulation through the system.

It will be understood that our apparatus will be constructed of suitable materials and that proper precautions for preventing heat losses and leakage will be observed. We find that many of the parts of our apparatus may be constructed of a steel containing about 16-23% chromium, about 7%-20% nickel and the balance substantially iron. This steel preferably has a content of carbon of about $\frac{1}{16}$ % or less. The steel may also contain small amounts of copper, silicon, molybdenum and tungsten.

The term "rotameter" as employed herein refers to liquid measuring devices.

It is, therefore, apparent that while we have described our invention in some detail, there are many changes that may be made therein without departing from the spirit of the invention.

What we claim is:

1. A chemical process which comprises forming a vapor containing acetaldehyde and formaldehyde, subjecting at least a part of the vapors to catalytic contact with an impregnated gel as a catalyst, maintained at a temperature between about 230° C. and 400° C.

2. A process for producing higher aliphatic aldehydes, which comprises reacting a mixture containing at least two different aliphatic aldehydes in the vapor phase and in contact with a catalyst essentially comprising a gel and from 45 to 50% of a metal salt catalyst, said catalyst being maintained at a temperature at least part of the time, whereby the reaction will take place under vapor phase conditions.

3. A process for producing higher aliphatic aldehydes, which comprises reacting a mixture containing at least two different aliphatic aldehydes in the vapor phase and in contact with a catalyst essentially comprising silica gel and metal salt catalyst, said catalyst being maintained at a temperature at least part of the time, whereby the reaction will take place under vapor phase conditions.

4. A process for producing higher aliphatic aldehydes, which comprises reacting a mixture containing at least two different aliphatic aldehydes in the vapor phase and in contact with a solid

catalyst essentially comprising alumina gel and a metal salt which is a catalyst, said catalyst being maintained at a temperature at least part of the time, whereby the reaction will take place under vapor phase conditions.

5. A process for producing higher aliphatic aldehydes, which comprises conducting a mixture containing at least two different aliphatic aldehydes in the vapor phase into contact with a gel as a catalyst maintained at a temperature, at least part of the time, whereby the reaction will take place under vapor phase conditions.

10 6. A process for the production of unsaturated aliphatic aldehydes, which comprises reacting formalin with another lower aliphatic aldehyde containing a greater number of carbon atoms, in the vapor phase and in the presence of a gel as a catalyst maintained at a temperature between about 200° C. and 400° C.

15 7. The chemical process which comprises reacting formaldehyde and acetaldehyde in the vapor phase and in the presence of a gel as a catalyst maintained at a temperature between about 250° C. and 400° C.

20 8. The chemical process for the production of a straight chain organic compound containing a double bond in the chain, which comprises passing vapor containing formaldehyde and acetaldehyde into contact with a gel as a catalyst maintained at a temperature between about 250° C. and 325° C.

25 9. A process for the production of aliphatic aldehyde compounds containing an odd number of carbon atoms in the molecule, which comprises vaporizing a saturated lower aliphatic aldehyde containing a lesser number of carbon atoms than the aldehyde being produced, vaporizing another lower aldehyde different from the aforementioned aldehydes, mixing the aldehyde vapors and contacting the vaporous mixture with a gel as a catalyst maintained at a temperature sufficient to cause reaction between the aldehyde vapors.

30 10. The chemical process which comprises vaporizing an aliphatic aldehyde containing less than four carbon atoms, vaporizing another and different aliphatic aldehyde, reacting together at least a part of the two aldehyde vapors in the presence of a gel as a catalyst maintained under temperature and pressure conditions which will cause reaction between the vaporized aldehydes, and recovering and separating the reaction products.

35 11. A process for producing higher aliphatic aldehydes, which comprises conducting a mixture containing at least two different aliphatic aldehydes in the vapor phase into contact with a silica gel as a catalyst maintained at a temperature, at least part of the time, whereby the reaction will take place under vapor phase conditions.

40 12. A process for producing higher aliphatic aldehydes, which comprises conducting a mixture containing at least two different aliphatic aldehydes in the vapor phase into contact with an alumina gel as a catalyst maintained at a temperature, at least part of the time, whereby the reaction will take place under vapor phase conditions.

45 13. The substantially continuous single-step chemical process for the production of vinyl aldehydes, which comprises contacting vapors having therein as essential components formaldehyde and another aliphatic aldehyde, this other aldehyde, relative to the quantity of formaldehyde, being present in excess, with a solid non-caustic catalyst, said process being carried out at a tem-

perature greater than 200° C., but less than 400° C., and at a space velocity between 300-2000.

14. The chemical process for the production of acroleins, which comprises passing a vapor containing formaldehyde and an excess of another lower aliphatic aldehyde in the contact with a solid non-caustic catalyst, maintained at a temperature between 250°-400° C.

15. The substantially continuous single-step chemical process for the production of acroleins, which comprises contacting vapors having therein as essential components formaldehyde and another aliphatic aldehyde, this other aldehyde, relative to the quantity of formaldehyde, being

present in excess, with a solid dehydrating catalyst, said process being carried out at a temperature greater than 200° C., but less than 400° C., and at a space velocity between 300-2000.

16. A process for producing unsaturated aliphatic aldehydes which comprises conducting a mixture containing at least two different aliphatic aldehydes in the vapor phase into contact with a solid dehydrating catalyst maintained at a temperature, at least part of the time, whereby the reaction will take place under vapor phase conditions.
